UNITED STATES PATENT OFFICE.

ELMER N. DOWNES, OF CHARLOTTE, NORTH CAROLINA.

DESIGN FOR A NON-SKID TIRE.

54,248.

Specification for Design.

Patented Dec. 9, 1919.

Application filed July 8, 1919. Serial No. 309,521. Term of patent 14 years.

To all whom it may concern:

Be it known that I, ELMER N. DOWNES, a citizen of the United States, residing at Charlotte, in the county of Mecklenburg and State of North Carolina, have invented a new, original, and ornamental Design for a Non-Skid Tire, as shown in the accompanying drawing, forming part of this specification.

In said drawing Figure 1 is an exterior face or edge view of part of the tire showing the peculiar bas relief ornamental con-

figuration thereof. Fig. 2 is a transverse sectional view on line 2—2, Fig. 1.

The design is in relief and extends longitudinally and circumferentially of the tire tread as indicated in the drawing.

I claim:

The ornamental design for a non-skid tire as shown.

ELMER N. DOWNES.
